CORSET, GIRDLE, AND LIKE GARMENT

Frank Batky, New York, N. Y., assignor to Carrie Berg, Henry Berg, Herbert Frankel, Maurice J. Frankel, and Joseph C. Frankel, all of New York, N. Y., copartners doing business as The Franco Corset Company, New York, N. Y.

Application January 5, 1933, Serial No. 650,259

3 Claims. (Cl. 2—36)

My invention relates to boning for corsets and the like.

Heretofore many corsets and like garments have been stayed by means of so called "strip boning", in which the stay of whalebone or equivalent material is backed on both sides by fabric and the fabric stitched to the garment closely adjacent to and along each edge of the stay. When the boning is on the inside of the garment, 10 as it usually is in corsets, the stitches securing the boning thereto extend through the body of the garment and are visible at the outside. In corsets and like garments, where the figures of the wearers vary greatly, it is often desirable to shorten one or more of the stays or to substitute a longer stay. With the boning of the prior art such as heretofore noted the stitching may be ripped and the necessary alteration in 15 the length of the stay made, after which the fabric strip may be restitched to the garment, but after such an alteration the appearance of the garment is often marred, and it is furthermore often a difficult operation to make the alteration suggested when the boning is rigidly secured at both edges.

My invention obviates many of the difficulties heretofore encountered in connection with boning of the prior art, and it is therefore the general object of the invention to provide an improved boning for corsets and the like.

It is a more specific object to provide boning for corsets and the like in connection with which alterations may be very readily made, and without marring the original appearance of the garment.

It is another object to provide boning for a garment in which the securing stitches for the boning may be placed practically where desired, so as to obviate the unsightliness of stitching 35 where not desired.

It is another object to provide as an article of manufacture improved boning which may be very readily and cheaply applied to garments.

Other objects will either be hereinafter noted 45 or will become apparent upon a reading of the specification taken in connection with the illustrative drawing.

Briefly stated, in a preferred form of the invention I provide a pocket for the bone or stay, 50 which is secured to the body of the garment, a portion being left free of the body to facilitate alterations. The boning, that is, what may be termed the stay or bone pocket, may be secured to the body at a point practically as remote as 55 desired from the stay, so that the securing stitches

may not appear where they would mar the appearance of the garment.

In the drawing which shows, for illustrative purposes only, a preferred form of the invention, illustrated as a step-in corset—

Fig. 1 is an outside view of the garment applied to the body of a wearer, parts being broken away to illustrate features of the invention;

Fig. 2 is an enlarged fragmentary inside view of a portion of the garment shown in Fig. 1 and 10 illustrating features of the invention;

Fig. 3 is an enlarged sectional view, taken substantially in the plane of the line 3—3 of Fig. 1.

In the form shown 1 represents a portion of fabric or panel forming a part of the body of the 15 garment, to which a second panel 2 is stitched, as indicated at 3. The panels 1—2 may be suitably bound at the top and bottom, as indicated at 4—5.

Heretofore, in such garments the fabric portions 1—2 would be stitched together with both edges terminating substantially at the line of stitching. In a garment as constructed by me and shown in the accompanying drawing, the fabric of the panel 1 of the garment is extended 25 at the inner side of the panel 2 beyond the edge of the latter panel so as to overlap and normally lie flatwise against the inside of said panel, being stitched thereto along the line 3. At the free edge of the overlapping portion of the panel 1, I 30 provide a pocket for the bone or stay. Such pocket is preferably formed by a strip or fabric 1", stitched to the portion 1' along spaced lines 6—7, as shown more particularly in Figs. 2 and 3. The stay 8 of whalebone or equivalent material is 35 held in the stay pocket and, if desired, the upper and lower ends of the pocket may be bound into the upper and lower edges of the garment at a point remote from the stitch line 3 by the stitching 4—5. If only a short stay, such as 8, is required or if a longer stay is shortened to suit a particular wearer, the stay may be positioned longitudinally in the pocket by means of cross stitching, as indicated at 9.

It will be seen particularly in Fig. 3 that the 45 stay pocket normally lies perfectly flat back of panel 2 and is free of the body of the garment. If it is desired to shorten a stay or substitute a longer one, the stay pocket may be lifted away from the panel 2 of the garment so that the 50 stitching 6 (or 7) readily ripped, the alteration made, and the stay pocket again stitched up, all without in any way affecting the stitching on the line 3.

In Fig. 2 a portion of the pocket is shown ripped 55

and turned back, as indicated at 10, affording access to the bone 8.

In the particular garment illustrated the double row of stitching 3 is quite remote from the bone or stay, and may be located relatively to the stay, where desired, so that the outside of the garment will not be marred by stitching, if stitching is not desirable along the line over the stay.

I have illustrated the flap or fabric portion securing the boning to the main body of the garment as being formed of an integral portion of the body of the garment, but it is to be understood that my improved boning or the pockets for the bone together with a securing flap corresponding to 1' could be separately made as units to be stitched to the body of a garment.

It is to be understood that my improved boning is not limited to corsets but is applicable to various other garments, such as girdles, surgical belts and the like, and the principles of the invention are also applicable to the more delicate feather boning for lingerie and the like. In fact, my improved boning may be used in place of most, if not all, of the boning heretofore in use.

While the invention has been described in considerable detail it is to be understood that various changes may be made within the scope of the invention as defined in the appended claims.

I claim:

1. In a garment of the character described, an outside fabric panel, a second fabric panel overlapping the inside of the first panel, the edge of the first panel being secured by stitches flatwise to

the second panel on a line remote from the edge of the overlapping portion of the latter, a stay pocket at the edge of the overlapping portion of the second panel formed by stitches other than those which secure said panels together, the overlapping portion and the stay pocket normally resting flatwise against the inside of the first panel.

2. In a garment of the character described, an outside fabric panel, a second fabric panel overlapping the inside of the first panel, the edge of the first panel being secured by stitches flatwise to the second panel on a line remote from the edge of the overlapping portion of the latter, a stay pocket at the edge of the overlapping portion of the second panel formed by stitches other than those which secure said panels together, the overlapping portion and the stay pocket normally resting flatwise against the inside of the first panel, with stitches securing the ends only of said stay pockets to the outside panel.

3. In a garment of the character described, an outside fabric panel, an inside fabric panel lying flatwise against the inside of said outside fabric panel and stitched thereto by a line of stitching remote from the free edge of said inside panel, a stay pocket formed at the free edge of said inside panel by stitching remote from and independent of said first mentioned stitching whereby said stay pocket of said panel may be lifted away from said outside panel to give free access thereto.

FRANK BATKY.
